UNITED STATES PATENT OFFICE.

PETER M. McNARY, OF PROVIDENCE, RHODE ISLAND.

DESIGN FOR A MEDAL, LOCKET, PIN, FOB, PENDANT, OR SIMILAR ARTICLE.

51,966.

Specification for Design.

Patented Apr. 9, 1918.

Application filed January 21, 1918. Serial No. 213,074. Term of patent 3½ years.

To all whom it may concern:

Be it known that I, PETER M. McNARY, a citizen of the United States, residing at the city of Providence, county of Providence, and State of Rhode Island, have invented a new, original, and ornamental Design for a Medal, Locket, Pin, Fob, Pendant, or Similar Article, reference being had to the accompanying drawing, forming a part thereof.

The figure is a face view of a medal, locket, pin, fob, pendant, or similar article illustrating my new design.

I claim:

The ornamental design for a medal, locket, pin, fob, pendant, or similar article, as shown.

PETER M. McNARY.

Witness:

HOWARD E. BARLOW.
